UNITED STATES PATENT OFFICE

108,550

DESIGN FOR A RESORT BUILDING

Terrence R. Morgan, Vancouver, Wash.

Application December 21, 1937, Serial No. 73,786

Term of patent 14 years

To all whom it may concern:

Be it known that I, Terrence R. Morgan, a citizen of the United States, residing at Vancouver, Clark County, Washington, have invented a new, original, and ornamental Design for Resort Buildings, of which the following is a specification, reference being had to the accompanying drawings, forming part thereof, wherein—

Fig. 1 is a front elevational view of a resort building, showing my new design.

Fig. 2 is a plan view of the same.

The side of the building opposite that shown in Fig. 1 is substantially the same in appearance as the side disclosed.

I claim:

The ornamental design for a resort building, as shown and described.

TERRENCE R. MORGAN.
